UNITED STATES PATENT OFFICE.

WILLIAM JAMES OLIVER, OF CHRISTCHURCH, NEW ZEALAND.

LIFTING OR SLING HOOK.

1,344,187.

Specification of Letters Patent. Patented June 22, 1920.

Application filed April 2, 1919. Serial No. 286,987.

To all whom it may concern:

Be it known that I, WILLIAM JAMES OLIVER, subject of the King of Great Britain, residing at Christchurch, in the 5 Dominion of New Zealand, have invented new and useful Improvements in Lifting or Sling Hooks; and I do hereby declare the following to be a full, clear, and exact description of the same.

10 This invention has been devised in order to provide an improved construction of sling hook used for lifting ships' cargo and other goods from a crane or like appliance and useful also for attachment to the falls 15 used in the lowering of ships' boats. The hook designed has for its primary object the provision of a construction that will automatically release itself from the sling when the hook is relieved from the weight 20 of the goods or article suspended thereon. Thus its use will provide that in the handling of cargo, ships' boats, or any other articles such cargo, boats or other articles will be automatically released from the lifting 25 gear when they have been deposited at the desired point and the suspension rope is slackened.

Combined with the hook are other means 30 designed with the object of tipping an article suspended on the hook, after it has been released from the hook, and then lifting it up in the tipped position. This feature is particularly serviceable in the handling of coal and such articles, to provide 35 for the basket in which the coal is placed, being lowered into the receptacle (such as a cart, ship's hold or the like) and then automatically released from its suspension afterward tipped up and lifted back to be 40 filled.

The invention consists broadly in constructing the sling hook of a suspension plate or frame that is attached to the lifting rope and is formed with a vertical slot 45 extending up from its bottom, and a hook proper that is pivoted in the frame so that it may swing in across the slot or may swing out therefrom and which hook is counterweighted beyond its pivot so that it is normally caused to swing out clear of the said slot. The pivot point of the hook is arranged in the vertical line of the lifting rope so that when a sling has been passed up into the slot and the hook is turned in 50 beneath such sling and the weight taken by the hook, the hook will be retained in the

inward position by the weight suspended thereon. When the hook is relieved from the weight its counterweighted end will be free to act, thus swinging the hook out and 60 releasing the sling in the required manner.

In fully describing the invention reference will be made to the accompanying sheet of drawings, in which:—

Figure 1 is a front elevation of the improved hook.

Fig. 2 is a side elevation thereof.

Fig. 3 is a sketch illustrating the manner of using the hook to automatically release and tip a coal basket suspended thereon.

The suspension frame is formed by an eye shank A, adapted to receive the lifting rope, and a plate B made in one therewith, or preferably two plates B, as shown in the drawings, extending parallel to one another 75 downward from the bottom of the shank A. These plates B, when two are used, are arranged at the required distance apart to permit of the hook C being placed in between them and pivoted, as at C', to swing 80 to and fro in a free manner. When the device is formed with a single plate, the hook is pivoted against one of its faces so that it may swing across it.

Each plate is formed with the slot E extending upward from its bottom edge in a line in the same plane as the shank A and lifting rope F, and this slot is made of such a width as to be adapted to receive the suspension sling of the weight to be lifted. 90 The slots in the two plates are coincident with one another.

The pivot pin C' of the hook is arranged in the same vertical plane as the lifting rope and the hook is so shaped that it may swing 95 across the slots E with its point well beyond the far side of the slots, or it may swing out to clear such slots. It is provided with an arm extension G beyond its pivot point and this arm is weighted to such an extent as to 100 overcome the weight of the hook and thus when the device is suspended for the hook to be swung out clear of the slots. When the hook is turned in to engage beneath a sling passed up into the slots, and the weight of such sling is taken by the hook, the hook will be retained in such position by reason of the pull thereon being in the vertical line of the shank and lifting rope, and also by reason of the curve in the hook. 110 Thus the sling will be effectually held on the hook and will be prevented from slip-

ping off it by its engagement between the slot sides, so long as the weight is suspended. When the weight is eased by lowering it on to a support, then the strain on the hook is relieved so that the weighted arm G will fall and swing the hook out from beneath the sling and thus free the sling from the device.

In order that any accidental release of the 10 sling from the hook may be prevented, such as for instance as might be likely to occur should a suspended sling of goods in its transfer from one point to another, engage or momentarily rest upon any fixture in its 15 path, the arm G may be retained in the raised position until such time as the lifting rope F has been fully slackened off, by means of a cord H that is made fast to the end of such arm and to a suitable point on 20 the lifting rope. This cord is made of such a length as to be fully extended when the lifting rope is straight and in this extended condition to hold the arm up. Thus when the lifting rope slackens, the cord H will 25 slacken also and permit the arm to fall and the hook to swing out.

If it is desired that the device may be capable of use as a fixed hook, provision may be made for locking the hook in its turned 30 in position. Means for this purpose consist in a pawl J that is pivoted to the frame member B and drops into a notch J' formed in the edge of the hook, and thus holds the hook from swinging out. This pawl and 35 the notch are situated on the other side of the pivot C' to that upon which the arm G extends.

The frame member or members B may be provided with an eye K fixed on each 40 side thereof at any convenient points clear of the working of the hook C. These eyes may be used for the attachment of the ends of ropes M (Fig. 3) the other ends of which are attached to the bottom of a coal basket 45 N suspended on the hook. Enough slack is left in these ropes to allow for the hook working to release the sling of the basket, and then when the lifting rope F is raised, for the ropes to turn the basket up and to 50 raise it with the hook, the basket being suspended bottom up, from the eyes K. Thus the device constructed and fitted in this way may be used to lower a basket of coal or other commodities, on to any desired point, 55 then to tip the basket up to discharge its contents, and then to raise the basket and return it to the point at which it is to be refilled, all without any handling at the discharging point and merely by the operations

of the winch or other appliance actuating 60 the lifting rope.

I claim:—

1. A sling hook formed by a frame member adapted to be suspended from a rope, constructed with a slot extending vertically 65 upward from its bottom end, in the line of the suspension rope, a hook member pivoted upon the face of such frame member at a point vertically above the slot and adapted to swing transversely in with its free end 70 across such slot or to swing out free of the slot, and having a weighted extension extending from the opposite side of its pivot and adapted to normally swing the hook clear of the slot in the frame member, and a 75 cord attached at its respective ends to the weighted arm and to the suspension rope, substantially as and for the purposes specified.

2. A sling hook formed by a frame member 80 adapted to be suspended from a rope, constructed with a slot extending vertically upward from its bottom end, in the line of the suspension rope, a hook member pivoted upon the face of such frame member at a point vertically above the slot and adapted to swing transversely in with its free end 85 across such slot or to swing out free of the slot, and having a weighted extension extending from the opposite side of its pivot 90 and adapted to normally swing the hook clear of the slot in the frame member, and a pawl pivoted to the face of the frame member adapted to engage the lock with the hook member.

3. A sling hook formed by a frame member 95 adapted to be suspended from a rope, constructed with a slot extending vertically upward from its bottom end, in the line of the suspension rope, a hook member pivoted 100 upon the face of such frame member at a point vertically above the slot and adapted to swing transversely in which its free end across such slot or to swing out free of the slot, and having a weighted extension extending from the opposite side of its pivot 105 and adapted to normally swing the hook clear of the slot in the frame member, and an eye fixed upon each side of the frame member.

In testimony whereof, I have signed this specification in the presence of two subscribing witnesses.

WILLIAM JAMES OLIVER.
